CALCULATING MACHINE

Francis A. Hosack, Rye, N. Y.

Application May 21, 1936, Serial No. 80,964

9 Claims. (Cl. 235—60)

This invention relates to calculating machines and particularly to that class in which totalling and listing operations are carried on in conjunction with the calculating functions. In my 5 Patent No. 1,823,859, issued September 15, 1931, I have disclosed locking devices controlling the actuator bars to prevent the printing of ciphers to the left of the registering values in adding and subtracting operations and by Patent No. 10 1,938,907 issued December 12, 1933, relates to cipher locks operating in conjunction with the bar locking devices to prevent such cipher printing in totalling operations.

The present application relates to mechanisms 15 for bringing the register pinions into and out of coacting relationship with the actuator bars at the proper times in adding, subtracting and totalling operations and has for an object thereof the coordination of such mechanisms with 20 the bar locking devices and cipher locks.

Other objects and advantages of the invention will be apparent upon consideration of the following description and appended claims when read in conjunction with the appended drawings 25 in which:

Fig. 1 is a sectional elevation at the left of the column of keys of highest denomination and shows the various parts in non-operated position;

30 Fig. 2 is a sectional view on the line 2—2 of Fig. 1 illustrating the manner in which the actuator bars cooperate with the key stems, and also shows the side frames of the machine;

Fig. 3 is a sectional view on the line 3—3 of 35 Fig. 1 and shows the bar locks for the actuator bars;

Fig. 4 is a sectional view on the line 4—4 of Fig. 1 and shows the zero locks for the actuator bars;

40 Fig. 5 is a fragmentary sectional elevation at the right of the column of keys of lowest denomination;

Fig. 6 is an enlarged view of part of Fig. 1 and shows certain of the mechanism for controlling 45 and operating the actuator bars;

Fig. 7 is an enlarged perspective view showing the key-stem lock releasing devices;

Fig. 8 is a fragmentary view corresponding to 50 part of Fig. 1 but showing the calculating pinions positioned for totalling operations; and

Fig. 9 is an enlarged perspective view of mechanism for controlling the demeshing of the calculating pinions in subtracting or totalling operations.

55 Figure 10 is an enlarged side view of a broken

detail of the accumulator gear frames and the various elements of mechanism associated therewith;

Figure 11 discloses a portion of the device including the bars for unmeshing the accumulator gears from the segmental gears and the associated mechanism for actuating them with the parts shown when the actuating handle is at initial position;

Figure 12 discloses the construction shown in 10 Figure 11, with the parts in the positions assumed when the actuating handle is in its forward position; and

Figure 13 is a view in section, with parts 15 broken away, taken on line 13—13 of Figure 1.

This application is a continuation in part of my copending application Serial No. 701,969 filed December 12, 1933, which is a division of Patent No. 1,938,907.

In Fig. 1 each of the keys 1 to 9 inclusive, of the 20 various columns making up the keyboard is held in its normal position by a compression spring 27 acting between plate 11 and a seat 28. Actuator bars 13, of which there is one for each column of keys, are provided adjacent their top and 25 bottom edges with laterally projecting stops 14, 15, 16 and 17 adapted to cooperate with a projecting portion 35 or 36 (Fig. 2) of a certain key of the column with which the bar is associated so that when the key is depressed and the bar is moved, the stop engages the projecting portion of the key to limit the operation of a printing segment 84 by the actuator bar to a number of increments of movement corresponding to 30 the value of the depressed key. The arrangement of the projecting portions on the various key stems and their relation to the stops on the actuator bar is more fully described in my prior Patent No. 1,823,859.

At one side of each column of key stems is a 40 key stem lock 29 journalled in the plates 30 and 31, so that it can swing into and out of engagement with laterally positioned depressions or notches 29b and 29c formed in the key stems adjacent their upper ends.

Near the forward end of each actuator bar 13 is a slot 38 for receiving a bar lock for the actuator bar and a slot 39 for receiving a zero lock for the actuator bar as shown in Fig. 5. Referring to Fig. 3, the bar locks consist of a series 50 of members 40, 41, 42, 43, one for each actuator bar, pivotally mounted on one side of the plate 38 at 44, 45, 46, 47. When no keys are depressed the bar locks depend perpendicularly, as indicated by the position at 40, with solid portions of 55

their lower ends in the slots 38 of the actuator bars and consequently all the actuator bars are locked against movement. Each bar lock is provided at its lower end with a slot 48, 49, 50, 51. 5 Laterally projecting members such as pins 52, 53, 54, 55, are carried by the bar locks and are engageable by arms 56, 57, 58, 59, secured to the key-stem lock trunnions 29a, which extend through plate 30, to move the bar locks so that 10 their slots register with actuator bars for the related column to permit their movement.

A single spring 60 associated with the right-hand bar lock 43 biases all the bar locks into locking relation with the slots 38 of the actuator bars. 15

The zero locks for the actuator bars comprise members 64, 65, 66, 67 (Fig. 4), pivoted on the other side of the plate 30 at 68, 69, 70, 71. The zero locks are biased by individual springs 72 so 20 that their lower ends rest in the slots 39 of the respective actuator bars. The slots 39 in each actuator bar is wider, as shown in Fig. 5, than the zero lock by an amount equal to the distance the actuator bar must travel to bring the printing segment 84, to be presently described, into position to print a zero. 25

The zero locks normally prevent the actuator bars 13 moving more than enough to bring the printing segments to zero position. Adjacent 30 their lower ends the zero locks are provided with projections such as pins 80, 81, 82, 83, adapted to be acted upon by arms 76, 77, 78, 79, carried by the key-stem locks 29 of the respective columns so that when a key is depressed in a column the 35 zero lock for the corresponding actuator bar 13 is moved out of the slot 39 in the bar permitting the bar to be moved to index the printing segment 84 in accordance with the value of the depressed key.

40 The bar locks and zero locks, when released, are held out of locking relation position by the arms 56, etc., or 76, etc., carried by the key-stem locks acting against the pins 52, etc., or 80, etc. This is because when a key is depressed the key-stem lock 29 is moved out of the notch 29b in the key stem and engages the notch 29c which is of lesser depth so that the key-stem lock does not return to its normal position until released from locking relation with the key stem. 45

50 Referring to Figs. 2 and 7, a bar 29d having a slot 29e for each key-stem lock 29 is provided for releasing the key-stem locks from the key stems, so that the depressed keys may be restored by their springs 27, and for moving the arms 56, 55, etc. and 76, etc., associated with the pins on the bar locks and zero locks, respectively, to permit locks which have been released to be restored to locking position by the springs associated therewith, as described in my copending application 55 Serial No. 701,970. The bar 29d is biased to normal position by a spring 29f so that the notches 29e are normally disposed to permit movement of any key-stem lock on depression of a key in the corresponding column.

65 Below actuator bars 13 and the main shaft 151 which has an operating handle, not shown, is the restoring frame shaft 103 (Figs. 1, 11 and 12). The restoring frame shaft has adjacent each end thereof an arm 151b connected by link 151c and 70 arm 151d to shaft 151. Shaft 103 is operable in one direction by main shaft 151 and in the opposite direction by springs 151e connected to pins 151f on arms 151b and to the frame of the machine at 151g. Mounted on the shaft 103 are the 75 restoring frames 104, one for each actuator bar,

having at their upper ends studs 105 which control the actuator bars 13.

The actuator bars have lugs 13d projecting through elongated slots in the plate 12 and connected to one end of springs 13c for moving the 5 actuator bars rearwardly, the other ends of the springs being connected to the plate at 13b. At their rearward ends the actuator bars 13 have racks 37 engaging toothed portions 85 of the printing segments 84, preferably mounted on a 10 common shaft 84a with proper provision for retaining them in alignment with the actuator bars. The printing segments 84 are illustrated as having printing portions 86 on their edges, the printing portions 86, as shown, being provided with 15 eleven divisions, one blank and the other comprising type from 0 to 9. A platen 88 and a ribbon 87 act in conjunction with the type on the segments 84 to effect printing.

The platen 88 has a shaft 89 supported adjacent each end by frames 88a pivoted at 88b and connected by links 88c to arms 88d carried by the main shaft 151. In order that the platen and ribbon may be moved against and away from the type faces at the proper times the links 88c have a pin and slot connection to frames 88a, so that the frames are moved by the main shaft at the end of the forward stroke of the operating handle. Springs 88f are provided to move the platen 88 away from segments 84. Shoulders 88r formed 30 on slots 88e in links 88c are adapted to engage studs 88h to move the platen frames 88a to effect printing. The links 88c have cams 88s engaging a bail 88t for raising the links 88c so that the platen 88 may be moved away from type faces 86 35 by springs 88f after printing has taken place, the studs 88h moving in the extensions 88u of the slots. 40

A bell crank 61, Fig. 3, is pivoted on plate 30, 45 engages the bar lock 40 at the extreme left and is connected by a link 61a to one end of a lever 61b, Figs. 1 and 6, pivotally mounted on plate 12. The other end of lever 61b extends adjacent restoring frame shaft 103 which is provided with a cam or stud 103c (Figures 1 and 6). Stud 103c is positioned for engaging and locking lever 61b to cause release of all bar locks after printing has taken place, to permit the previously locked actuator bars to be moved one increment rearwardly by springs 13c. This increment of rearward movement is provided to insure that all bars are positioned for effecting such transfer operations as may be necessary and also to permit totalizer engagement with driving segments 84, 50 as subsequently described. 55

Numerical wheel pinions 90, each associated with a cam 91 so that a pinion and cam move together, are mounted on a shaft 94, (Figures 1, 10 and 13) which is supported by a frame 92 adjacent each end. The frames 92 are pivoted on a shaft 93 and springs 92a, connected between the shafts 84a and 94, are provided to bias the pinions 90 into engagements with the toothed portions 85 of the segments 84. Forward of each numerical wheel pinion 90 is a pinion lock 95 having teeth adapted to mesh with the pinion 90 to retain the latter in its operated position. 60

A latch 92b pivoted at 92c is provided for each frame 92 and is biased into engagement therewith by a spring 92d for normally holding the numerical pinions 90 out of engagement with the toothed portions 85. The studs 105 of two of the restoring frames 104, those adjacent the pinion frame 92, extend laterally from their frames 104 and are adapted to engage and release the 75

latches 92b on rotation of the arm 104 in a counterclockwise direction as the actuating handle on shaft 151 is pulled forward as shown in Figure 12.

5 Pivots on a shaft 101a supported by an extension 100 of each frame 92 are transfer levers 101, one for each numeral wheel pinion except that of the highest order (Figure 10). One end 101b of each lever 101 engages the corresponding cam 91 so that when a numeral pinion passes from 9 to 0 position, the raised portion 91a of the cam causes the lower end 101c of the lever to be moved out of the path of movement of a stop 102 adjacent the rack 37 on the actuator bar 13 associated with the numeral pinion of the next higher order. For example, the transfer mechanism illustrated in my copending application Serial No. 81,198 may be employed, and is illustrated herein. The frame 92 is retracted after an additive transfer by means of the bar 138 slidably mounted on the frame of the calculating device and normally urged toward the frame 92 by spring 139. The bar 138 is moved to the right against the tension of the spring by the lever 141 pivotally mounted at 141a and carrying at its lower end a pivoted latch 141e normally urged clockwise by a spring 141f but normally maintained in alignment with the lever 141 by an abutment 141g carried thereby. The lever 141 is rocked counterclockwise by engagement with pin 151h on link 151c. On pulling the actuating handle on shaft 151 forward, latch 141e engages pin 138a on bar 138 and urges it to the right until latch 140 engages in a notch in bar 138. Continued clockwise rotation of shaft 151 causes counterclockwise rotation of lever 104 until pins 105 trip latch 92b allowing the frame 92 to swing to the left engaging gears 98 with gear teeth 85. Prior to tripping of latch 92b the actuator bars 13 have set the printing segments 84 to positions corresponding to the keys depressed.

Rearward movement of the actuating handle rotates shaft 151 counterclockwise, shaft 103 clockwise and levers 104 and pins 105 move bars 13 forward rotating printing sectors 84 and accumulator gears 90 to produce an additive reading on the accumulator. At the end of the return movement of the actuator handle cam 138 trips latch 140, releasing the bar 138 which is driven to the left against frame 92 by spring 139 to disengage gears 98 and relatch frame 92 with latch 92b.

A subtraction step is similarly produced with the exception that the frame 92 is released by tripping latch 92b prior to rearward movement of bars 13, so that the gears 98 mesh with gears 85 during rearward movement of bars 13 and are unmeshed at the end of the rearward movement. This action is produced by the following mechanism.

The movement of the bars 138 and the associated mechanisms is best shown in Figs. 11 and 12. With the elements of the device in the position shown in Fig. 11, the device is in condition for transfer operation. Fig. 12 illustrates the relative positions of the parts of the device at the time the frames are released to mesh the accumulator gears with the segmental gears.

70 A subtracting lever 98b projecting through the casing is secured to shaft 98c and is connected to a link 98d (Figures 1 and 10). The shaft 98c extends transversely of the machine and has fixed thereto adjacent its other end an arm 98e connected to a link 98g, Fig. 5. As shown in

Figures 9 and 10 the link 98d has a slot 98k which receives a stud 98h on an extension 98l of the lever 98. The lever 98 is pivotally mounted on a shaft 98s extending across the frame of the device. The link 98g is similarly connected to a lever 98 adjacent the other frame 92. Springs 98a bias the levers 98 to the position shown in Figs. 1 and 9. The levers 98 support balls 101d and 101e, the ball 101d acting on upward movement of levers 98 to move the end 101b of each adding transfer lever 101 from contact with the cams 91. The transfer levers 101 are retained in displaced position by friction or by any other suitable means. The frames 92 rock rearwardly and forwardly, as indicated previously, during adding and subtracting operations carrying the transfer levers 101 with them. The ball 101e is normally positioned to engage the ends 101c of transfer levers 101 in their forward position and restore the latter to engagement with the cams 91 at the end of an operating cycle. Springs 98i bias the lever 98b and the parts connected thereto to normal position.

In order that pinions 90 may be meshed with the toothed portions 85 of the printing segments 84 at the proper time for effecting subtraction, the lever 98b is operatively connected to slides 62, one of which is mounted on each of the frames 92 and suitably guided at 62a for vertical movement as shown in Figures 9 and 10. The links 98d and 98g operable by shaft 98c are connected to bell cranks 98p, each pivotally mounted on a frame 92. The bell cranks 98p each have a slot 98r receiving a stud or floating connecting pin 62d, also extending into a slot 62e in the corresponding slide 62. The connections 62d, 98r permit movement of the frames 92 without actuating links 98d and 98g, and the connections 62d, 62e permit movement of the slides without moving the links, whereas the rocking of bell cranks 98p by subtracting lever 98b through the links acts through studs 62d to raise the slides. Adjacent its lower end each slide carries a stud 62b, Figures 1 and 10, adapted to engage the arm 63a of a bell crank pivoted on the frame of the machine at 63b. The other arm 63c of each bell crank pivotally supports a latch tripping member 92f adapted on rocking of the bell crank to engage a pin 92g on the pinion frame latch 92b to move the latter about 50 its pivot out of latching relation with the associated pinion frame 92. A spring 63d is connected to trip 92f and pivot 63b for restoring trip 92f and bell crank 63a.

Referring again to Figures 9 and 10, slide 62 has a cutout portion 62c which normally registers with a cutout portion 92i on the adjacent frame 92. When the pinions are in engagement with the toothed portions 85 of sectors 84, the slots 62c, 92i, normally permit the free movement of studs 88g carried by the links 88c connecting the platen frames 88a to the main shaft 151. When the slides 62 are raised the cutout portions 62c move from registration with the cutout portions 92i of frames 92 and solid portions of the slides align with the cutout portions of the frames so that the studs 88g may act to cause demeshing of the pinions 90 from the toothed portions 85 of the printing segments at the proper times. The studs 88g are carried by members 88k guided for sliding movement on links 88c and extend through slots 88l in the links. Springs 88n connect member 88k and pins 88p on the links. The springs 88n are preferably stronger than springs 92a and act when 75

extended by contact of studs 88g with slides 62 to move frames 92 to disengage pinions 90 from the toothed portions 85 at the end of the printing operation and to maintain the pinions 90 meshed until latches 92b become effective to hold the frames 92 against movement in subtracting and totalling operations; as will be described.

A total key 74 and subtotal key 75 are guided 10 in the plates 10 and 11. A key-stem lock 74a, Fig. 4, similar to locks 29 for the numerical keys is provided for engaging notches in the keys 74 and 75 to maintain the latter in depressed position until the lock is released, whereupon 15 the keys may be raised by their springs. Key-stem lock 74a is operatively connected by link 74c, 74e with locks 29 for the numeral keys so that it is released therewith. A shaft 74h extends transversely of the machine and adjacent 20 one end has an arm 74i (Fig. 5), and adjacent the other end a bell crank 74k. One arm of bell crank 74k is connected to total key 74 so that depression of the latter rocks the shaft 74h. The other arm of the bell crank and the arm 74i 25 are connected by links 74l and 74n to levers 74p which are pivotally mounted on the slides 62. The links 74l and 74n have pin and slot connections 74r to the levers 74p, and are restrained to substantially linear movement so that movement 30 of links 74l and 74n by depression of key 74 causes slides 62 to be raised.

The total key has a lug 74g positioned above a lug 75c on the subtotal key (Figure 1), so that depression of the total key also effects depression of the subtotal key. The subtotal key is connected to one arm of a bell crank 75d fixed to a shaft 75e. As shown in Figure 10, the other arm of bell crank 75d is connected by a link 75f to an arm 129b on shaft 129 on which cipher locks 134 are pivotally mounted. Cipher locks 134 are controlled by levers 124, operable by pinions cams 91, and by latches 135 to prevent cipher printing to the left of a significant figure in totalling operations as described in my 45 Patent 1,938,907. The shaft 75e extends transversely of the machine and adjacent its other end carries an arm 75g (Figures 5 and 13) connected by a link 75h to another arm 129b also mounted on the shaft 129. The shaft 129 is 50 mounted for vertical movement in guides on the main frame of the device. The arrangement is such that depression of the subtotal key, or depression of the total key acting through the lugs 74g and 75c on the total and subtotal keys, 55 causes a toggle movement of the links 75f and 75h rearwardly moving shaft 129 upwardly in its guides, and this upward movement causes the ends of the cipher locks 134 to move into position to be engaged by shoulders 133 on 60 the actuator bars.

The links 75f and 75h are connected to bell cranks 75k, one of which is pivotally mounted adjacent each frame 92. The bell cranks 75k are also connected to members 75l each having 65 at their upper ends a seat 75n resting beneath one of the levers 98 (Figures 9 and 10). The members 75l are adapted on operation of the subtotal key, either directly or from the total key, to raise the members 75n and turn levers 70 98. This movement of levers 98 is only enough to cause movement of the ends 101c of transfer levers 101 sufficiently to disengage them from the stops 102 on actuator bars 13 and thereby 75 permit movement of frames 92 to cause engagement of pinions 90 with the toothed parts of

segments 84. However, this movement of transfer levers 101 is not great enough to move the ends 101b of the levers from the paths of the raised portions 91b of cams 91 and thus the transfer levers remain effective to serve as zero stops for the pinions 90. The links 75f and 75h are also provided with studs 75i for engaging the arms 63a of the bell cranks to cause release of the frame latches 92b.

The lug 75c on subtotal key 75 is adapted to 10 engage and operate a bell crank 73a associated with the zero locks 64, etc. (Fig. 4). A suitably guided bar 73, operable by bell crank 73a, and having slots 73b, into which the pins 80, etc., carried by the zero locks extend, is provided for simultaneously releasing all the zero locks. Key 75 also has a lug 75a for operating bell crank 61 which pertains to the bar locks 40, etc. (Fig. 3). Thus, operation of subtotal key 75, directly or from total key 74, effects simultaneous release of the bar locks and zero locks for all the actuator bars.

Other elements which would be embodied in a complete machine to operate in conjunction with the subtracting lever 98b, and total and subtotal keys 74, 75 for registering and listing functions are disclosed in my Patent No. 1,938,907 but are omitted herein to simplify the present disclosure.

The operation is as follows:

When a key in any column is depressed the key-stem lock 29 for that column is moved out of engagement with the notch 29b of the key stem. The arm 51, for example, moves with its key-stem lock and acts on pin 53 of the bar lock 41 moving the slot 49 into alignment with the actuator bar 13 to permit its movement. This is illustrated in Fig. 3, where depression of a key in the fifth column from the right has caused the key-stem lock 29 of that column to move arm 57 releasing bar lock 41 for actuator bar 13 of the fifth column. The bar lock 41 has caused the release of the bar locks for the actuator bars of all columns to the right. It should be noted that the bar locks 40 for the columns to the left of the fifth column remain in locking position. It should also be noted that unless a key is depressed in a particular column the related key-stem lock 29 is not released, the pin 54, 55 on the bar lock moving therewith away from the arm 58, 59, carried by the key-stem lock. This is illustrated in the first, third and fourth columns, while the position of the arm 59a indicates that a key has been depressed in the second column also.

The arm 77 also moves with the key-stem lock 29 for the fifth column and acts on the pin 81 on the zero lock 65 for that column moving zero lock 65 out of the notch 39 in the actuator bar 13. As the key is depressed, the key stem portion between notches 29b and 29c acts on key-stem locks 29 to cause the bar locks and zero locks to be moved slightly beyond released position by arms 57, 59a and 77, 78. Springs 60 and 72 act on the right bar lock and the released zero locks to move arms 57, 59a and 77, 78, through studs 53, 55a, etc. and 81, 82 to move the key-stem locks sufficiently to engage notches 29c to hold the keys in depressed position.

When the operating handle secured to the main shaft 151 is moved forwardly, the restoring frame shaft 103 is moved counterclockwise carrying the restoring frames 104 and permitting springs 13c to move the actuator bars rearwardly (Figures 1, 11 and 12). The actuator bars for 75

columns in which keys have been depressed, having their bar and zero locks released, move rearwardly until a stop, such as 14, on these actuator bars engages a projection 35 of the key stem for limiting the movement of the printing segments by racks 37 to an amount corresponding to the value of the depressed keys.

The combination of the bar locks and the zero locks insures the printing of zeros to the right of any key which is depressed and inhibits the movement of any actuator bars to the left of that key. This is for the reason that any bar lock which is thrown out carries all of its right hand neighbors with it to permit the actuator bars for these columns to move at least enough to index the printing segments in zero printing position while the zero locks normally release individually and only on depression of keys in the corresponding columns. The actuator bars for columns to the right of a column in which a key has been depressed move rearwardly a single step to move the printing segments 84 for these columns to zero printing position, the movement of these bars being limited by their zero locks. Bars 13 for columns in which keys have been depressed have their zero locks released and move rearwardly a number of increments corresponding to one more than the value of the key depressed. The actuator bars to the left of the amount entered on the keys are held by their bar locks and do not follow the movement of the restoring frames 104.

As the restoring frame shaft is rotated the cams 136 turn therewith and pin 151h rocks the lever 141 retracting bars 138 from pinion frames 92 to permit numeral pinions 90 to be moved by springs 92a from engagement with pinion locks 95 and into engagement with the toothed portions 85 of printing segments 84, as will be later described. However, pinions 90 do not engage the toothed portions 85 during the rearward movement of the actuator bars in addition, inasmuch as the pinion frames are still held by the latches 92b.

After the segments 84 have been indexed in printing position the studs 105 of restoring frames 104 move rearwardly therewith away from the actuator bars 13 which are held by the key-stem stops, bar locks, or zero locks, as the case may be.

The platen frames 88a are brought forwardly by the main shaft 151 through the arms 88d and links 88c and subsequently to the termination of the rearward movement of the actuator bars the platen 88 and the ribbon 87 engage the type portions 86 of the segments 84 which have been adjusted to the printing line in accordance with the movement of the actuator bars. After links 88c have moved the platen against the type faces the forward movement of the links 88c causes the cams 88s to engage the bail 88t bringing the slots 88u into register with the studs 88h on the platen frames. Springs 88f then act on the platen frames to move the platen away from the type faces as studs 88h move in the parts 88u of the slots 88e.

After printing has been effected the stud 103c moving with restoring frame shaft 103 strikes the inner end of and moves lever 61b clockwise as viewed in Fig. 6 about the pivot and acting through link 61a turns bell crank 61 shown in Fig. 3. This movement of bell crank 61 moves all the non-released bar locks 40 about their pivots to released position with the slots at lower ends of the locks in alignment with the actuator bars 13. The previously locked actuator bars,

those to the left of the fifth column under the conditions assumed above, are then moved rearwardly by their springs 13c a single increment, the movement of the bars being limited by the engagement of the rearward end of slots 39 with the zero locks.

At the end of the forward stroke of the operating handle the studs 105 on the restoring frames adjacent pinion frames 92 contact the latches 92b as shown in Figure 12, disengaging the latter from the pinion frames, which are then moved rearwardly by the springs 92a so that the pinions 90 move from engagement with the pinion locks 95 and into engagement with the toothed portions 85 of the printing segments.

When the operating handle is released the main springs 151e, which were tensioned during the rearward movement of the restoring frames 104, turn restoring frame shaft 103 carrying frames 104 therewith to engage the actuator bars for moving them forwardly. The studs 105 on the restoring frames adjacent the pinion frames 92 move from engagement with the latches 92b and the springs 92d move these latches into position for subsequently locking the pinion frames.

When studs 105 reengage the actuator bars the latter are moved forwardly and the racks 37 thereon restore the printing segments 84 and the toothed portions 85 thereof, being engaged with the pinions 90, operate the pinions in accordance with the numerals entered on the keyboard. As the actuator bars move forwardly the stops 102 engage the ends 101c of transfer levers 101 which hold the actuator bars one step from normal position.

During return movement of the actuator handle, the lever 141 rotates clockwise from the position shown in Figure 12, and pivoted portion 141e rocks to pass the pin 138a to return to the position shown in Figures 1 and 11.

In the event that any numeral pinion 90 has been rotated from the nine position through the zero position, the raised portions 91a of the cam 91 associated with that pinion rocks the corresponding transfer lever 101 rearwardly, moving the end 101c of the transfer lever out of the path of the stop 102 on the bar 13 of next higher order, in preparation for the transfer operation which is performed in the manner described.

At the end of the rearward movement of the operating handle the cams 136 on shaft 103 effect the release of the bars 138 for engagement with pinion frames 92. The impact of the bars 138 rocks the pinion frames 92 to move pinions 90 from engagement with the toothed portions 85 and into engagement with the pinion locks 95. As the pinion frames 92 are moved rearwardly the transfer levers 101 are carried therewith and the ends 101c of the transfer levers 101 which have been tripped to effect a transfer engage the bail 101e carried by the levers 98 and are restored to normal position.

As the pinions 90 are demeshed the frames 92 move latches 92b downwardly and studs 92h move with frames 92 to permit the springs 63d to position trip members 92f above the pins 92g on the latches (Fig. 1). Latches 92b, biased by springs 92d, engage frames 92 and lock the pinions 90 in their non-meshing position.

As a lever 29h is turned about its pivot at or near the end of forward movement of actuator bar 13, it moves the bar 29d laterally as described in application Serial No. 701,970, so that the shoulders of the notches 29e engage the key-stem locks 29 moving the latter from engagement with the

notches 29c of the key stems. The springs 27 associated with the depressed keys return the latter to normal position.

The bar 29d is returned to normal position by 5 the spring 29f. On return of the bar 29d the shoulders of the notches 29e move away from the key-stem locks 29. The spring 60 associated with the bar lock of lowest denomination, acts to pivot all the released bar locks so that the slots 10 48 etc. are moved from registration with the actuator bars and the solid portions of the bar locks are moved into the notches 38 of the actuator bars to lock the latter in normal position. The individual springs 72 associated with the 15 released zero locks move the zero locks so that their ends are positioned in the notches 39 in the actuator bars. The key-stem locks again engage the key stem notches 29b as the arms 56, etc., and 76, etc., are moved by the pins on the bar locks and zero locks.

When a number is to be subtracted the subtracting lever 98b is moved to and held in operative position. It is to be understood that latching means of any desired form may be provided for retaining the lever 98b in operated position if it is not desired to manually hold it in operative position. Lever 98b acts through the links 98d and 98g to move the levers 98 about their pivots. The levers 98 act through bail 101d 30 to move the ends 101b of the transfer levers from engagement with the pinion cams 91 and out of the paths of movement of the raised portions 91a thereof to permit subtractive movements of pinions 90 through zero position if required.

35 The movement of links 98d and 98g by subtracting lever 98b also rocks bell cranks 98p and the slides 62 are moved upwardly on pinion frames 92 so that the cutout portions 62c move from registration with the frame notches 92i and solid portions 40 of the slides become aligned therewith. The studs 62b adjacent the ends of the slides engage the arms 63a of bell cranks 63 and turn the latter to move the latch trips 92f which contact the pins 92g on the latches 92b, moving 45 the latches out of engagement with the pinion frames 92, so that springs 92 may act to mesh the pinions 90 with toothed portions 85 for operation during the rearward movement of released actuator bars. The frames 92 then are 50 retained out of the position in which the accumulator gears can mesh with the segmental gears by the bars 138.

The depression of numeral keys controls the actuator bars in movement as previously described; when the operating handle is moved forwardly the shaft 103 turns and the cams 136 permit the levers 141 to retract the bars 138.

Some slight movement of the frame 92 in a counterclockwise direction will result on release 60 of the elements above described. Then, as the actuating handle is pulled forward, the main drive shaft 151 will be rotated clockwise and the bar 138 will be retracted or moved forwardly by the pivoted lever 141. The frames 92 move with 65 the bars 138 and the actuator bars 13 will also move rearwardly. The early movement of the actuator bars is extremely short but permits the accumulator gears to engage the segmental gears 84. This first rearward movement of the 70 actuator bars 13 is equivalent to the displacement of only one numeral position on the printer. That is, those segmental gears 84 which are permitted to move, can move only from blank to zero position before the accumulator gears 90 engage the 75 segmental gears 84. Due to the fact that the

teeth of both the segmental gears 84 and the accumulator gears 90 are large, they will mesh sufficiently accurately during the rearward movement of frame 92 to prevent any inaccuracy in the position of the accumulator gears relative to the segmental gears. Thus the teeth on the accumulator gears 90 will be disposed somewhere between the proper teeth on the segmental gears 84 and will be correctly positioned when these gears come into full mesh. Upon continued forward movement of the actuating handle, the parts associated therewith will move to the positions shown in Figure 12 and the actuator bars 13 will move rearwardly a sufficient distance to properly index the segmental gears 84 and the accumulator gears 90.

After the actuator bars have indexed the printing segments in printing position, platen 88 is moved against the type faces to effect printing, as previously described. After printing has taken place, studs 88g carried by links 88c move toward the notches 92i in the pinion frames and since these notches are now closed by the slides 62 the studs 88g engage the slides 62 on the frames 92.

In the arrangement described, the studs 88g are carried on members 88k to which springs 88n are connected (Figure 9). Consequently, on engagement of studs 88g with slides 62 the springs 88n are further tensioned by the pins 88p moving with links 88c while studs 88g are temporarily held by engagement with slides 62. On tensioning of the springs 88n, which are stronger than springs 92a associated with frames 92, they act to move the frames to carry the pinions 92 from toothed portions 85 and into engagement with pinion locks 95. Studs 88g may be fixed to links 88c and act directly on the frames but are preferably resiliently mounted thereon for a purpose which will hereinafter become apparent. As the pinions 90 are demeshed the pins 92h on frames 92 permit the springs 63d to move the latch trips 92f rearwardly against pins 92g on latches 92b, which, however, are held away from frames 92 by the studs 105.

When the operating handle is released and moves rearwardly, the main springs 151e act to move the restoring frames 104 forwardly. The studs 105 move away from the latches 92b which are moved by their springs 92d to engage the pinion frames 92 for holding the pinions 90 out of engagement with the toothed portions 85 and in engagement with the pinion locks 95. As the links 88c are moved rearwardly the studs 88g move from engagement with the slides 62 on pinion frames 92, the arrangement being such that the studs 105 move more rapidly than the studs 88g, so that the latches 92b may maintain the pinions demeshed during the return of the bars 13. The springs 88n act to maintain the studs 88g against the slides 62 on the frames 92 as the pins 88p move with links 88c until the latches 92b engage the frames 92 after the studs 105 have moved away from the latches. As suggested above, the studs 88g might be fixed to links 88c and act directly on the frames. The resilient mounting of studs 88g is provided as a precautionary measure, in addition to the difference in rate of movement of studs 105 and links 88c, to insure engagement of latches 92b when links 88c move rearwardly and studs 105 move away from the 70 latches.

As the restoring frames 104 turn with the shaft 103 they drive the actuator bars forwardly toward normal position and restore the printing segments to position their blank portions at the 75

printing line, but they do not effect operation of the numeral pinions 90 which are held in disengaged relation by the latches 92b. If, during the prior rearward movement of the actuator bars, any of the numeral pinions 90 had moved from zero through the nine position (subtractively), the pinion of higher order is operated to effect the transfer by suitable mechanism such as disclosed in my Patent No. 1,938,907.

10 The cams 136 turn with the restoring frame shaft 103 and release the bars 138 for engagement with the pinion frames 92 at the end of the rearward stroke of the operating handle for further locking the numeral pinions in engagement with the pinion locks 95. Before the pinion frames are engaged by the bars 138, restoring frames 104 move the actuator bars to restore all of the actuator bars to their normal position. The key-stem locks, released bar locks, and zero locks are actuated by the operation of the cams 13a on the actuator bar or bars, and the bar locks, zero locks and depressed keys are restored to normal position, all as previously described.

25 At the end of the subtracting operation the subtracting lever 98b is released. When latching means are provided for this lever, as suggested above, the release of such latches may be effected automatically in any desired manner. On release of the subtracting lever 98b it is restored by springs 98i and operates links 98d and 98g to permit springs 98a to rock levers 98 downwardly so that the bail 101e carried by the levers 98 engages the transfer levers 101 moving their ends 101c into engagement with pinion cams 91. Levers 98d and 98g also turn bell cranks 98p to move the slides 62 downwardly moving the studs 62b away from the arm 63a of the bell cranks. The bell cranks are restored and the latch members 92f are again positioned by springs 63d above the pin 92g on the latches 92b. The springs 92d of latches 92b restore the latches with pins 92g in contact with the ends of trip members 92f.

40 When total key 74 is depressed the shaft 14h is turned and acts through links 74l and 74n to move the slides 62 upwardly. This upward movement of the slides 62 does not affect the lever 98b because of the pin and slot connection 62d, 62e. The pins 62b near the end of slides 62 also act on the bell cranks 63 for operating the latch tripping members 92f to release latches 92b to permit meshing pinions 90 with toothed segments 84 during the rearward movement of the actuator bars.

45 It will be remembered that the total key has a lug 74g which overlaps a lug 75c on the subtotal key 75, so that depression of the total key also affects depression of the subtotal key. Consequently, when key 74 is operated the links 75f and 75h are operated through shaft 75e and act on the arms 129b on shaft 129 to move the cipher locks 134 upwardly so that their upper ends are positioned adjacent the shoulders 133 on the actuator bars. After a series of adding or subtracting operations have been performed, some of the numeral pinions 90 have moved away from the zero position, either by the entry of amounts through operation of keys in corresponding columns or as a result of transfer operations, and have their cams 91 positioned so that the raised portion 91b of cam 91 is out of engagement with the corresponding cipher lock lever 124. The springs 132 associated with these 50 cipher lock levers turn the levers about the shaft

10a to maintain the upper end of the levers in contact with the cams 91 and the lower end 126 of each lever acts on the corresponding cipher lock 134 to move the latter rearwardly about the shaft 129, the force of the springs 131 associated with the cipher locks 134 being overcome by the superior springs 132 associated with the cipher lock levers. Thus, certain of the cipher locks 134 have been moved rearwardly about the shaft 129 to inoperative position, so that their upper 10 ends are positioned out of the path of movement of shoulders 133 on the corresponding actuator bars.

15 The cipher locks 134 for all denominations to the right of any column in which a numeral has been entered are also swung about the shaft 129 so that their ends are out of the path of the shoulders 133. This is effected by cooperative relation of the cipher locks to permit the printing of ciphers to the right of a column having a 20 numeral therein, as disclosed in my Patent No. 1,938,907.

25 The movement of links 75f and 75h also causes the studs 75i to engage the arms of bell cranks 63 moving the latch tripping members 92f 25 for releasing the latches from engaging relation with the pinion frames 92. Pins 62b on slides 62 also perform this function on depression of the total key itself. Although there is a seeming duplication of function, it may be stated that pins 30 62b are provided especially for effecting release of the latches on subtracting operations as previously described.

35 Depression of subtotal key 75 by total key 74 also acts through studs 75c and 75a on the subtotal key to move the bell cranks 61 and 73a (Figs. 3 and 4), so that all of the bar locks and all of the zero locks are simultaneously released to permit the actuator bars to move in accordance with the amount entered in the numeral 40 pinions 90.

45 When the operating handle connected to the main shaft is moved forwardly the restoring frame shaft 103 is turned and the cams 136 carried therewith to permit the lever 141 to retract the bars 138 from engagement with the pinion frames 92. The pinion frames 92 are thereupon moved by the springs 92a so that the numeral pinions 90 move from engagement with the pinion locks 95 into engagement with the toothed portions 85 of the printing segments 84, Fig. 8 50 in the manner described in connection with a subtracting operation.

55 As frame 92 moves the latches 135 engage those cipher locks 134 having their ends positioned in the path of shoulders 133 in order to hold the locks firmly in raised position. The latches 135 cannot engage the corresponding cipher locks 134 which have been moved about shaft 129 by levers 124 since either figures or zeros are to be printed in the corresponding columns.

60 As the frames 92 move the pins 92h swing the trips 92f from engagement with pins 92g and latches 92b are operated by springs 92d to engage the frames.

65 When the shaft 103 turns the restoring frames 104 move therewith, permitting the actuator bars 13 to be moved rearwardly by their springs 13c. As the frames 104 move and prior to engagement 70 of pinions 90 the released bars 13 index the corresponding printers in zero printing position. This insures printing of zeros to the right of pinions having figures therein.

75 The actuator bars 13 for columns in which 75

numbers have been entered move rearwardly to an extent determined by the number entered in the numeral pinions, the movement of the pinions and the indexing of the printing segments being limited by the engagement of the raised portion 91b of cams 91 with the ends 101b of the transfer levers 101 which act as zero stops for the pinions. The actuator bars 13 for columns to the left of the amount on the numeral pinions are held against any movement as the related cipher locks 134 have their upper ends positioned in the paths of movement of and are held firmly against the shoulders 133 on these actuator bars as a result of operation of the total key.

15 After the amount on the numeral pinions 90 has been transferred to the printing segments 84, the platen 88 is moved through links 88c against the printing segment to effect printing of the total. After printing has taken place in a totalling operation the studs 88g on the links 88c engage the slides 62 and rock the pinion frames forwardly so that the pinions 90 demesh from the toothed segments 85 and engaged the pinion locks 95, as described for subtraction.

20 When the operating handle on the main shaft is released and moves rearwardly the studs 105 on the restoring frames 104 move away from the latches 92b, which engage the pinion frames 92 to hold the pinions demeshed during the forward movement of the actuator bars by the restoring frames 104, as in subtraction.

25 As the restoring frames 104 move the actuator bars 13 to normal position, the racks 37 move the printing segments 84 so that the blank spaces are again presented at the printing line. In the final movement of the actuator bars, key-stem locks, bar locks and zero locks are restored to locking relation with the actuator bars, all as previously described. The movement of the bar 29d to release the key-stem locks, bar locks and zero locks also effects releasing of the key-stem lock 74a for the total key and subtotal key which are restored to normal position by their springs. On restoration 30 of the subtotal key the links 75f and 75h move the cipher locks and members 75i to normal position.

35 On restoration of total key 74 the slides 62, latch trip 92f, etc., are restored to normal position on movement of the links 75i and 75n. The springs 131, 132 associated with the cipher locks and the cipher lock levers also act to restore the latter to their normal position.

40 When the subtotal key is depressed to take a subtotal, the operation is as described above, except that slides 62, being connected to the total key but not to the subtotal key, are not moved upwardly and the studs 88g on the links 88c cannot act to demesh the numeral pinions 90 from the toothed portions 85 of the sectors 84 after printing has taken place. Consequently, during the restoring operation of bars 13, the printing sectors and the pinions are operated by the racks 37, the printing segments being restored to blank position and the numeral pinions being operated to reinsert the amount in the pinions. At the end of the rearward stroke of the operating handle the bars 138 are driven against the pinion frames 92 by release of the latches 140 and effect demeshing of the pinions 90 from the toothed portions 85 of segments 84, as in addition.

45 It should be noted that in addition the latches 92a maintain the pinions from operative relation with the actuator bars during their rearward

5 movement and that when printing has been effected the restoring frame studs 105 release the latches. In subtracting, totalling and subtotaling operations the latches are released immediately upon operation of the control lever or keys but the pinions do not become operatively engaged with the actuator bars in their rearward stroke until the active printing members are indexed to zero positions because of the control of the pinion frames by the restoring frame shaft 10 acting through bars 138.

15 The slides 62 carried by the frames are also directly controlled by the subtracting lever and total key to demesh the pinions at the end of the rearward stroke of the bars so that the forward bar movement does not affect the pinions. Since the subtotal key does not operate the slides 62 the pinions are actuated in both movements of the bars so that the registered value is restored to the pinions.

20 It should be understood that many of the parts illustrated are shown in a form chosen purely for simplicity of illustration and to provide a complete showing of related parts and do not necessarily represent preferred embodiments. For example, the mechanism for moving the platen frame to effect printing and for moving it away from the type faces after printing is illustrated only for completeness of description and may be replaced by various well known types of printing mechanisms.

25 As there are many changes and variations which may be made in the form of my invention without departing from the spirit thereof, I desire to include all such variations and changes within the scope of the appended claims.

30 I claim:

1. In a calculating machine the combination of 35 accumulating pinions; reciprocable actuator bars for operating said portions; a frame supporting said pinions; means for moving said frame to operatively associate said pinions with said actuator bars; latches for said frame normally acting to maintain said pinions out of operative relation to said bars during movement of the latter in one direction; a calculating function control member; means controlled by said member for releasing said latches to enable operative association of said pinions and actuator bars during said movement of the latter; means for moving said frame to discontinue the operative relation 40 between said pinions and said bars at the end of said movement of the latter, said means being normally ineffective to move said frame; and means responsive to said control member for rendering said frame moving means effective to cause discontinuance of the operative relation between said pinions and said actuator bars at the end of said movement thereof.

45 2. In a calculating machine, the combination of 45 accumulating pinions; printing members; reciprocable actuator bars engaged with said printing members; a frame supporting said pinions; means for moving said frame to operatively associate said pinions with said bars; means for moving said bars in one direction to index said members in printing position; latches for said frame acting to maintain said pinions out of operative relation with said bars; means operable for releasing said latches to cause operative association of said pinions and actuator bars during said movement of the latter; selectively operable subtracting, and totalling keys for actuating said releasing means; normally inoperative means for moving said frame to discontinue the oper- 50

ative relation between said pinions and said bar at the end of said movement of the latter; a slide carried by said frame; and means controlled by said keys for positioning said slide for engagement by said frame moving means to cause said discontinuance of the operative relation between said pinions and bars.

3. In a calculating machine, the combination of accumulating pinions; printing members; reciprocable actuator bars engaged with said printing members; a frame supporting said pinions; means for moving said frame to operatively associate said pinions with said bars; means for moving said bars in one direction to index said members in printing position; latches for said frame acting to maintain said pinions out of operative relation with said bars; a slide carried by said frame; means actuated by said slide on operation thereof for releasing said latches to cause association of said pinions and bars during said movement of the latter; selectively operable subtracting and totalling keys; normally inoperative means for moving said frame to discontinue the operative relation between said pinions and said bars at the end of said movement of the latter; and means controlled by said keys for positioning said slide for engagement by said frame moving means to cause said discontinuance of the operative relation between said pinions and bars at the end of said bar movement.

4. In a calculating machine, the combination of accumulating pinions; printing members; reciprocable actuator bars engaged with said printing members; a frame supporting said pinions; means for moving said frame to operatively associate said pinions with said bars; means for moving said bars in one direction to index said members in printing position; latches for said frame acting to maintain said pinions out of operative relation with said bars during said movement of the latter; individual bar locks for holding said bars against movement; depressible keys for the respective bars acting on depression thereof to release the corresponding bar locks; locking means acting between said frame and bars to prevent said movement of said frame when the bar lock corresponding to any bar has not been released; a shaft; means controlled by said shaft and operative at the end of said bar movement for releasing all said bar locks to render said frame locking means inoperative; means subsequently operable by said shaft for releasing said frame latches to cause association of said pinions and actuator bars; and restoring frames operable by said shaft for moving said actuator bars in the opposite direction to actuate said pinions.

5. In a calculating machine, the combination of accumulating pinions; printing members; reciprocable actuator bars engaged with said printing members; a frame supporting said pinions; means for moving said frame to operatively associate said pinions with said bars; means for moving said bars in one direction to index said member in printing position; latches engaging said frame to hold said pinions out of operative relation with said bars during said movement of the latter; individual bar locks for holding said bars against movement; depressible keys for the respective bars acting on depression thereof to release the corresponding bar locks, locking means acting between said frame and bars to prevent said movement of said frame when a bar lock corresponding to any bar has not been released; a shaft; means controlled by said shaft

and operative at the end of said bar movement for releasing all said bar locks to render said frame locking means inoperative; means subsequently operable by said shaft for releasing said frame latches to cause association of said pinions and actuator bars; restoring frames operable by said shaft for moving said actuator bars in the opposite direction to actuate said pinions; and means operable by said shaft for moving said frame to discontinue the operative relation between said pinions and said actuator bars.

6. In a calculating machine; the combination of movable actuator bars; accumulating pinions; a pinion frame movable to operatively associate said pinions with said bars for actuation thereby; locking means for preventing movement of said bars; transfer trip means carried by said frame and acting between each pinion and the actuator bar of next higher order to control the latter for effecting transfers; stops on said bars lockingly engaging the related transfer trip means and acting thereon to prevent movement of said frame for operatively associating said pinions with their actuator bars when said bars are restrained by said locking means; and means for releasing said locking means for all bars to interrupt the locking engagement between said bar stops and said transfer trip means prior to movement of said frame.

7. In a calculating machine; the combination of movable actuator bars; accumulating pinions; a pinion frame movable to operatively associate said pinions with said bars for actuation thereby; locking means for preventing movement of said bars; transfer trip means carried by said frame and acting between each pinion and the actuator bar of next higher order to control the latter for effecting transfers; stops on said bars lockingly engaging the related transfer trip means and acting thereon to prevent movement of said frame for operatively associating said pinions with their actuator bars when said bars are restrained by said locking means; subtracting control means; and means responsive to said control means for moving said transfer trip means from locking engagement with said bar stops prior to movement of said frame.

8. In a calculating machine; the combination of movable actuator bars; accumulating pinions; a pinion frame movable to operatively associate said pinions with said bars for actuation thereby; latching means associated with said frame for holding said pinions from operative relation with said bars; locking means for preventing movement of said bars; transfer trip means carried by said frame and acting between each pinion and the actuator bar of next higher order to control the latter for effecting transfers; stops on said bars lockingly associating said transfer trip means and acting thereon to prevent movement of said frame to associate said pinions with their actuator bars when any bar is restrained by its locking means; means for releasing said latching means to permit movement of said frame; and means for releasing said locking means for all bars to interrupt the locking engagement between said bar stops and transfer trip means prior to movement of said frame.

9. In a calculating machine; the combination of movable actuator bars; accumulating pinions; a pinion frame movable to operatively associate said pinions with said bars for actuation thereby; latching means associated with said frame for holding said pinions from operative relation with said bars; locking means for preventing movement

of said bars; transfer trip means carried by said frame and acting between each pinion and the actuator bar of next higher order to control the latter for effecting transfers; stops on said bars lockingly associating said transfer trip means and acting thereon to prevent movement of said frame to associate said pinions with their actuator bars when any bar is restrained by its locking means; subtracting control means; totalling

control means; means selectively operable by said control means for releasing said frame latching means; and means selectively operable by said control means for releasing said locking means for all bars to disengage said transfer trip means from said bar stops prior to movement of said frame. 5

FRANCIS A. HOSACK.

CERTIFICATE OF CORRECTION.

Patent No. 2,166,066.

July 11, 1939.

FRANCIS A. HOSACK.

It is hereby certified that error appears in the printed specification of the above numbered patent requiring correction as follows: Page 1, first column, line 9, for the word "by" read my; same page, second column, line 22, for "compresison" read compression; page 3, second column, line 59, for "wth" read with; page 8, second column, line 40, claim 1, for the word "portions" read pinions; and that the said Letters Patent should be read with this correction therein that the same may conform to the record of the case in the Patent Office.

Signed and sealed this 22nd day of August, A. D. 1939.

Leslie Frazer

(Seal)

Acting Commissioner of Patents.
